(57) **CLAIM**

The ornamental design for a dustpan, as shown.

DESCRIPTION

FIG. 1 is a top perspective view of a dustpan showing my new design;

FIG. 2 is a left side elevational view thereof;

FIG. 3 is a front elevational view thereof;

FIG. 4 is a top plan view thereof;

FIG. 5 is a rear elevational view thereof;

FIG. 6 is a right devotional view thereof; and,

FIG. 7 is a bottom plan view thereof.

The broken lines shown in FIGS. 2 and 6 represent portions of the dustpan that form no part of the claimed design.
